US0D1030747S

(12) **United States Design Patent** (10) **Patent No.:** **US D1,030,747 S**
(45) **Date of Patent:** **** Jun. 11, 2024**

(54) **ELECTRONIC DEVICE**

(71) Applicant: **Samsung Electronics Co., Ltd.**, Suwon-si (KR)

(72) Inventors: **Namhyun Kang**, Suwon-si (KR); **Minah Koh**, Suwon-si (KR)

(73) Assignee: **SAMSUNG ELECTRONICS CO., LTD.**, Suwon-si (KR)

(**) Term: **15 Years**

(21) Appl. No.: **29/833,653**

(22) Filed: **Apr. 6, 2022**

(30) **Foreign Application Priority Data**

Dec. 30, 2021 (KR) 30-2021-0063276

(51) **LOC (14) Cl.** **14-02**

(52) **U.S. Cl.**

USPC **D14/341**

(58) **Field of Classification Search**

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The evenly-dashed broken lines in the drawings illustrate portions of the electronic device that form no part of the claimed design.

1 Claim, 6 Drawing Sheets
